UNITED STATES PATENT OFFICE

1,989,257

DRAPERY HARDWARE

Archie A. Allen, Sturgis, Mich., assignor to Kirsch
Company, Sturgis, Mich.

Application May 17, 1934, Serial No. 726,121

7 Claims. (Cl. 156—19)

The main objects of this invention are:

First, to provide a flexible metal eyelet tape for draperies and the like, which is well adapted for a variety of uses, and which can be conveniently conformed and secured to supports of various shapes and sizes.

Second, to provide a device of this character which can be used on the outside as well as on the inside of a supporting casing.

Third, to provide a new article of manufacture of this character, which is simple and economical in construction, and very effective for the purpose intended.

Further objects relating to details and economies will appear from the description. A preferred embodiment of my invention is illustrated in the accompanying drawings, in which:

Fig. 1 is a fragmentary perspective view of a flexible metal eyelet tape embodying the features of my invention.

Fig. 2 is a fragmentary transverse section showing my tape secured to the front of a vertical support.

Fig. 3 is a similar view showing the device secured to the bottom of a horizontal support such as a shelf.

Fig. 4 is a fragmentary plan view showing how the tape is conformed for use with an angled support.

Fig. 5 is a fragmentary plan showing the tape partially encircling a column.

Fig. 6 is a fragmentary perspective view of the tape bent at right angles to itself and vertically offset.

Fig. 7 is a fragmentary view in front elevation showing my drapery eyelet tape attached to the inner and outer sides of an arch.

Fig. 8 is a fragmentary view in front elevation of the tape connected to a horizontal support such as a shelf rod by means of a hanger.

Fig. 9 is a fragmentary view in front elevation of the device in use on an odd-shaped window or doorway.

Fig. 10 illustrates the tape in use in supporting valances and the like in a store window.

The parts will be identified by their numerals of reference which are the same in all the views.

1 is an angle tape preferably of sheet metal, having flanges disposed at right angles to each other. One of the flanges consists of a longitudinal series of spaced triangular projections 2 having central eyelet openings 3 adjacent their apexes. The other flange consists of a longitudinal series of spaced rectangular projections 4

having central openings 5 adjacent their outer edges.

The triangular and rectangular projections are of substantially the same length, and are arranged so that the centers of the projections of one lie in the same transverse planes as the centers of the spaces between adjacent projections of the other. Thus, the device can be bent and conformed into an almost unlimited number of different shapes. The rectangular projections 4 are primarily provided by me for securing the tape to the supporting member. Holes 5 are for attachment by screw or nail. The projections 2 with eyelet holes 3 are used as hangers. The openings 3 receive the hooks or pins of the draperies or curtains.

In Fig. 2, 6 is a supporting member such as a window or door casing and 7 is a screw securing the tape or rod to the front of said member.

In Fig. 3, 8 is a supporting member such as a casing, by device 1 being secured to the inner or under side thereof by the screw 7. In this case, the projections 2 depend in the manner illustrated.

Referring to Fig. 4, 9 is an angular supporting member to which my curtain or drapery supporting tape 1 is secured. It is bent so as to conform to the shape of the supporting member as shown. In this connection, it should be noted that the openings 5 in the projection 4 are in the bending area and facilitate the bending.

In Fig. 5, 10 is a round columnar post encircled by my device, the device being secured to the post by means of the screws 7.

In Fig. 6, I show my device bent at substantially right angles to itself, one portion 11 thereof being vertically offset relative to the other portion 12. This is very desirable in some installations.

In Fig. 7, 13 is an arch having my flexible metal tape secured to the inner side 14 thereof, and to the front 15 thereof adjacent the upper edge of the arch. In this case, the projections 2 of the inner strip extend inwardly, whereas the corresponding projections of the outer strip extend forwardly.

In Fig. 8, 17, 18 are rod hangers which support my tape 1 in spaced relation beneath the horizontal support 6.

Fig. 9 illustrates the use of my device on an odd-shaped window or doorway 18, the device being secured to the inner side of the frame.

In Fig. 10, 21 is the top of a store window having my tape 1 secured to the lower side thereof.

Another important use of my device is on the

inside of a cornice. Various other uses will readily suggest themselves as the occasions arise. It is believed that sufficient uses have been shown to illustrate the adaptability of my tape.

5 Having thus described my invention, what I claim as new and desire to secure by Letters Patent is:

1. A device of the character set forth, comprising a flexible angle member of sheet metal having flanges disposed at right angles to each other, one of said flanges consisting of a longitudinal series of spaced triangular projections having central openings adjacent their apexes, and the other flange consisting of a longitudinal series of spaced rectangular projections having central openings adjacent their outer edges, the triangular and rectangular projections being of substantially the same length and being arranged so that the centers of the projections of one series lie in the same transverse planes as the centers of the spaces between adjacent projections of the other.
- 10 2. A device of the character set forth, comprising an angle member having flanges disposed at right angles to each other, one of said flanges consisting of a longitudinal series of spaced projections having central openings, and the other flange consisting of a longitudinal series of spaced rectangular projections having central openings adjacent their outer edges, the projections being of substantially the same length and being arranged so that the centers of the projections of one series lie in the same transverse planes as the centers of the spaces between adjacent projections of the other.
- 15 3. A device of the character set forth, comprising an angle member of bendable material having flanges each consisting of a longitudinal series of spaced projections having central openings adjacent their outer edges, the projections being of substantially the same length and being arranged so that the centers of the projections of one series lie in the same transverse planes as the centers of the spaces between adjacent projections of the other.
- 20 4. A device of the character set forth, comprising an angle member of bendable material having flanges each consisting of a longitudinal series of spaced triangular projections, and the other flange consisting of a longitudinal series of spaced rectangular projections, the triangular and rectangular projections being of substantially the same length and being arranged so that the centers of the projections of one series lie in the same transverse planes as the centers of the spaces between adjacent projections of the other.
- 25 5. A device of the character set forth, comprising an angle member of bendable material having flanges each consisting of a longitudinal series of spaced projections, the projections being arranged so that the centers of the projections of one series lie in the same transverse planes as the centers of the spaces between adjacent projections of the other.
- 30 6. A device of the character set forth, comprising an angle member of sheet metal having flanges disposed at right angles to each other, one of said flanges consisting of a longitudinal series of spaced triangular projections, and the other flange consisting of a longitudinal series of spaced rectangular projections, the triangular and rectangular projections being of substantially the same length and being arranged so that the centers of the projections of one series lie in the same transverse planes as the centers of the spaces between adjacent projections of the other.
- 35 7. A device of the character set forth, comprising an angle member having flanges, one of said flanges consisting of a longitudinal series of spaced triangular projections, and the other flange consisting of a longitudinal series of spaced rectangular projections.

40 ARCHIE A. ALLEN.

ranged so that the centers of the projections of one series lie in the same transverse planes as the centers of the spaces between adjacent projections of the other.

4. A device of the character set forth, comprising an angle member of bendable material having flanges each consisting of a longitudinal series of spaced projections, the projections being of substantially the same length and being arranged so that the centers of the projections of one series lie in the same transverse planes as the centers of the spaces between adjacent projections of the other.

5. A device of the character set forth, comprising an angle member of bendable material having flanges each consisting of a longitudinal series of spaced projections, the projections being arranged so that the centers of the projections of one series lie in the same transverse planes as the centers of the spaces between adjacent projections of the other.

6. A device of the character set forth, comprising an angle member of sheet metal having flanges disposed at right angles to each other, one of said flanges consisting of a longitudinal series of spaced triangular projections, and the other flange consisting of a longitudinal series of spaced rectangular projections, the triangular and rectangular projections being of substantially the same length and being arranged so that the centers of the projections of one series lie in the same transverse planes as the centers of the spaces between adjacent projections of the other.

7. A device of the character set forth, comprising an angle member having flanges, one of said flanges consisting of a longitudinal series of spaced triangular projections, and the other flange consisting of a longitudinal series of spaced rectangular projections.
